DESIGN FOR A CENTER BRIDGE FOR EYEGLASSES

Edgar R. Durgin, Newark, N. J., assignor to New Jersey Optical Co., Newark, N. J., a corporation of New Jersey

Application July 15, 1936, Serial No. 63,846

Term of patent 7 years

To all whom it may concern:

Be it known that I, Edgar R. Durgin, a citizen of the United States, residing at Newark, in the county of Essex and State of New Jersey, have invented a new, original, and ornamental Design for Center Bridge for Eyeglasses, of which the following is a specification, reference being had to the accompanying drawing, forming part thereof.

In said drawing, Fig. 1 is a top edge view; Fig. 2 is a front face view; Fig. 3 is a side edge view of a center bridge for eyeglasses, showing my new design, and Fig. 4 is a cross sectional view taken on line 4—4 in Fig. 2.

I claim:

The ornamental design for a center bridge for eyeglasses, as shown.

EDGAR R. DURGIN.
